UNITED STATES PATENT OFFICE.

OLUF TYBERG, OF BROOKLYN, NEW YORK.

DESIGN FOR A MILLING-MACHINE COLUMN.

SPECIFICATION forming part of Design No. 28,123, dated January 4, 1898.

Application filed October 8, 1897. Serial No. 654,595. Term of patent 14 years.

To all whom it may concern:

Be it known that I, OLUF TYBERG, a citizen of the United States, residing at Brooklyn, in the county of Kings, State of New York, have 5 invented a new and original Design for Columns for Milling-Machines, of which the following is a specification, reference being had to the accompanying drawings, forming a part thereof.

10 Figure 1 is a side elevation of a column constructed in accordance with my improved design. Fig. 2 is a horizontal section on the line 2 2 of Fig. 1; Fig. 3, an elevation at right angles to Fig. 1, the lower portion being broken 15 away.

In the drawings, A shows the ordinary base-plate of a milling-machine column, the column B rising therefrom, as usual, at one side of the center of the base-plate and adjacent 20 to one of the corners thereof. The column is shown as rectangular in cross-section, and that is the usual cross-section of the columns of ordinary milling-machines. In this design, however, the vertical guide or way C is at- 25 tached to or formed upon the column at one corner thereof, as clearly shown in the drawings—that is to say, the column has two converging sides D D', and the way C is located at the angle of the column formed by these 30 sides, or, in other words, at the corner of the column common to these sides and symmetrically arranged with reference to them, and

this corner of the column is in the drawings shown as that corner farthest removed from the corner of the base-plate adjacent to which the column is located. Above the vertical way C and parallel with one of the sides of the column converging on the way, in this case the side D, is a vertical face E, shown as of circular outline and as consisting of a plate-like structure and having its rear connected with the top of the column proper by inclined ribs or braces E'.

The essence of this design does not consist in surface ornamentation or in the precise 45 outline or contour of the several portions of the column and way; but the essence of the design resides, essentially, in the new location of the vertical way with reference to the column—that is to say, the essence of the design 50 consists in a column having converging sides at the angle or junction of which, or at the corner of the column common to both of which, the vertical way is located.

Having described my invention, what I 55 claim as new, and desire to secure by Letters Patent, is—

The design for a milling-machine column, substantially as herein shown and described.

OLUF TYBERG.
